US00D891281S

(12) **United States Design Patent** (10) Patent No.: **US D891,281 S**
Ho (45) Date of Patent: **** Jul. 28, 2020**

(54) **LIGHTNING PROTECTION DEVICE**

(71) Applicant: **EquiVolt M Pte Ltd**, Singapore (SG)

(72) Inventor: **Wei Chon Alvin Ho**, Singapore (SG)

(73) Assignee: **EquiVolt M Pte Ltd**, Singapore (SG)

(**) Term: **15 Years**

(21) Appl. No.: **35/506,916**

(22) Filed: **Jan. 4, 2019**

(80) **Hague Agreement Data**

Int. Filing Date: **Jan. 4, 2019**

Int. Reg. No.: **DM/201328**

Int. Reg. Date: **Jan. 4, 2019**

Int. Reg. Pub. Date: **Jun. 14, 2019**

(30) **Foreign Application Priority Data**

Sep. 3, 2018 (CN) 2018 3 0492630

(51) **LOC (12) Cl.** **10-05**

(52) **U.S. Cl.**

USPC **D10/105**

(58) **Field of Classification Search**

USPC D10/105; D13/129, 130, 131, 132
